UNITED STATES PATENT OFFICE.

ALBERT KINDLER, OF SAN DIEGO, CALIFORNIA.

RADIATOR-SUBHEATER.

1,111,309.

Specification of Letters Patent. Patented Sept. 22, 1914.

Application filed August 25, 1913. Serial No. 786,449.

To all whom it may concern:

Be it known that I, ALBERT KINDLER, a citizen of the United States, and a resident of San Diego, in the county of San Diego and State of California, have invented certain new and useful Improvements in Radiator-Subheaters, of which the following is a specification.

My invention relates to a device to be used in connection with the ordinary steam radiator for heating the same by the use of an ordinary gas burner, and the objects of my invention are, first, to provide a sub-heater for radiators whereby an ordinary steam radiator is supported and the water in said radiator heated by means of a pipe manifold immediately over the gas burner; second, to provide a sub-heater for radiators which is inclosed and will not be affected by drafts of air, etc.; third, to provide such a device that may be made applicable to different kinds of makes of steam radiators; and fourth, to provide such a device that is simple, economical of construction, easily operated and easily installed.

With these and other objects in view as will appear hereinafter, my invention consists of certain novel features of construction, combination and arrangement of parts as will be hereinafter described in detail and particularly set forth in the appended claims, reference being had to the accompanying drawings and to the characters of reference thereon which form a part of this specification, in which:—

Figure 1 is a front elevational view of my device complete, shown in connection with a gas burner and a steam radiator mounted therein, and Fig. 2 is a top view thereof showing a portion broken away and in section to facilitate the illustration.

Similar characters of reference refer to similar parts throughout the several views.

45 The casing 1, pipes 2, manifolds 3, elbows 4, elbows 5, coupling 6 and intake 7, constitute the principal parts of my device.

The casing 1 is rectangularly shaped as shown and is an inclosed box except that 50 near the middle on the top side is provided a vent 1^a and in the top is provided a plurality of holes 1^b adapted for the lower ends of the steam radiator to fit into. In each corner is provided a lug 1^c adapted to support the legs of the radiator. The front is

provided with a grate which may be covered up with a door if desired. Through the open space of this grate the air is allowed to enter sufficiently to produce proper combustion. Connecting with the inlet and outlet of the radiator, on each end are the elbows 5, one on each end, and connecting with one of these is another elbow 4, and with the other a short nipple and coupling 6 which connects with the elbow 4 so that 60 the one end is lower than the other. Into these elbows 4, on each side, are mounted the manifolds 3, one on each end. These manifolds 3 are adapted to support and connect with the radiator, the pipes 2 extending longitudinally beneath said radiator. These pipes are preferably of thin copper and there may be any number desired, preferably four. Immediately beneath this 65 manifold of copper pipes the gas burner is placed so that the blaze from the burner will heat the thin copper pipes which are 70 filled with water from the radiator which provide immediate circulation and cause the water to circulate in said radiator. In the 75 one end of the radiator 7, a short distance from the bottom, is provided a pipe with a cap on the upper end adapted for a feed for water into said radiator, as there should be from four to six inches of water in the 80 bottom of said radiator.

Though I have shown and described a particular construction, combination and arrangement of parts, I do not wish to be limited to this particular construction, combination and arrangement, but desire to include in the purview of my invention the construction, combination and arrangement substantially as set forth in the appended 85 claims.

It is obvious that with this construction there is provided a sub-heater for radiators which is applicable to the different makes of radiators, that the pipe manifold will be readily heated by the flame from the gas 90 burner which will heat the water therein, cause immediate circulation and will rapidly heat the water in the radiator, which operation is a great deal more efficient than applying the flame on the lower surface of the 95 radiator; that the burner is inclosed so that drafts will not affect the burner, and may be closed up if desired; that the device is simple, economical, easily constructed and easily installed.

Having thus described my invention, what I claim as new and desire to secure by Letters Patent, is:

1. A sub-heater for steam radiators comprising a rectangularly shaped support adapted to inclose the lower end of an ordinary steam radiator, means therein for supporting said steam radiator on its legs, a pipe manifold mounted in said sub-heater so that when the radiator is mounted therein said manifold is directly below said radiator, means for connecting the ends of said pipe manifold with the opposite ends of the steam radiator and means mounted below and adjacent to said manifold for heating the same.
2. A sub-heater for ordinary steam radiators comprising a rectangularly shaped support adapted to inclose a portion of the lower end of a radiator so that said radiator may be readily removed therefrom, means mounted therein for supporting the legs of said steam radiator, a pipe manifold mounted in said support at an angle thereto, means for connecting the ends of said pipe manifold with the opposite ends of said radiator and a gas burner mounted below and adjacent to said manifold and parallel thereto.
3. In combination with an ordinary steam radiator, a sub-heater comprising a rectangularly shaped support adapted to inclose a portion of the lower end of said ordinary steam radiator so that said radiator may be

readily removed therefrom, a means mounted therein for supporting said legs of said radiator, a pipe manifold mounted therein, means for connecting the ends of said pipe manifold with the opposite ends of said radiator, a gas burner mounted below and adjacent to said manifold adapted for heating said manifold, a grate in the front of said sub-heater and vent means on the top and back side thereof.

4. In a device of the class described the combination of a rectangularly shaped support provided with oblong holes in its upper surface adapted for the insertion of the lower end of an ordinary steam radiator therein, means in said support for supporting the legs of said steam radiator, a pipe manifold mounted therein longitudinally thereof, means for connecting the opposite ends of said manifold with the opposite ends of said steam radiator when in position therein, a pipe gas burner mounted beneath said manifold in said support adjacent thereto, a grate in the front of said support and a vent in the upper end and back side thereof.

In testimony whereof, I have hereunto subscribed my name in the presence of two subscribing witnesses:

ALBERT KINDLER.
